US0D1041576S

(12) **United States Design Patent** (10) **Patent No.:** **US D1,041,576 S**
(45) **Date of Patent:** **** Sep. 10, 2024**

(54) **FINGER TOY**

(71) Applicant: **Weihua Xiao**, Shenzhen (CN)

(72) Inventor: **Weihua Xiao**, Shenzhen (CN)

(**) Term: **15 Years**

(21) Appl. No.: **29/918,112**

(22) Filed: **Nov. 24, 2023**

(30) **Foreign Application Priority Data**

Jun. 21, 2023 (CN) 202330385271.3

(51) **LOC (14) Cl.** **21-01**

(52) **U.S. Cl.**

USPC **D21/447**; D21/468

(58) **Field of Classification Search**

USPC D21/394, 436, 442, 447, 455, 466, 468,

(57) **CLAIM**

The ornamental design for finger toy, as shown and described.

DESCRIPTION

FIG. 1 is a perspective view of finger toy showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

Colour forms no part of the claimed design.

1 Claim, 8 Drawing Sheets
